CLAIM

The ornamental design for a hand held vacuum body, as shown and described.

DESCRIPTION

FIG. 1 is a perspective view of a hand held vacuum body showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof; and,

FIG. 8 is a perspective view thereof upon its insertion into an associated base.

The base outlined in broken lines in FIG. 8 forms no part of the claimed design.
